H. HUMM.
MATCH CONTAINER.
APPLICATION FILED MAY 31, 1919.

1,335,970.

Patented Apr. 6, 1920.

INVENTOR
Hans Humm

BY Frank Ledermann
his ATTORNEY

UNITED STATES PATENT OFFICE.

HANS HUMM, OF BROOKLYN, NEW YORK.

MATCH-CONTAINER.

1,335,970.

Specification of Letters Patent.

Patented Apr. 6, 1920.

Application filed May 31, 1919. Serial No. 300,977.

To all whom it may concern:

Be it known that I, HANS HUMM, citizen of the Republic of Switzerland, resident of Brooklyn, in the county of Kings and State 5 of New York, have invented certain new and useful Improvements in Match-Containers, of which the following is a specification.

This invention relates generally to match 10 containers, and more particularly to such devices which have means for delivering a single match at a time into a tray at the bottom thereof, the match having been meanwhile ignited.

15 The object of my invention is to provide such a match container of simple and novel construction, inexpensive to manufacture, and readily operable by anybody.

This and other objects will become apparent in the description below, in which characters of reference refer to like-named parts on the drawings.

Figure 1 is a side elevational view of my device.

25 Fig. 2 is a central sectional elevational view of the same, taken on the plane $a-a$ of Fig. 3.

Fig. 3 is a front elevational view of the same.

30 Referring in detail to the drawings, 1 represents the frame or casing of my device having an upwardly projecting rear member 2 provided with holes or slots 3 for securing the device to a wall. A cover 4 is hinged to the top of the side members and provided with a folded projection 5 adapted to coöperate with a ridge 6 in the front member of the casing to lock said cover. Said front member is inclined as shown to 40 provide a substantially funnel-shaped chamber.

The side members are constructed as shown at 7 in Fig. 1, with bearings 8 adapted to support the ends of a drum shaft 9.

45 A drum 10 having a number of longitudinal peripheral slots or grooves 11 is mounted on said shaft, said grooves being of a depth and width to comfortably receive a match. A narrowed, curved, spring band 12 projects downward from said front member in surface contact with the periphery of the drum 10. The side members 7 are cut to provide extending ears 13 and 14, the latter being bent slightly inward and having 50 roughened inside surfaces 15. A narrowed

receiving tray 19 is secured to the other ears 13, as shown.

A curved plate 16 is secured inside the chamber to the rear member 2 of the casing, as shown in Figs. 2 and 3, extending in 60 whole to the periphery of drum 10; thereafter its sides are prolonged as spring-fingers 17, which pass between the side members 7 and the drum 10, extending a short distance outward from the drum at the front 65 of the device. The lower extremity of the rear member 2 is looped throughout its width, as shown in Fig. 2, said loop removably locking said drum by engaging a groove 11. One end of the drum shaft 9 is provided with a thumb piece or handle 18, for turning the drum.

The operation of the device is now apparent. Matches are contained in the chamber as shown by 20 in Fig. 2. On turning 75 the handle 19 in the direction of the arrow of Fig. 2, a single match, previously embedded in a groove 11, is carried downward by the drum 10 toward the tray 19. As the match leaves the chamber, it is engaged by the 80 spring band 12, which contacts with the upper surface of the match and prevents the match from falling from the groove.

After traveling a short distance from the chamber, the ends of the match, which project from the ends of the drum, are engaged by the spring fingers 17, which clamp the match against the band 12. As the match is carried forward, it gradually pushes said fingers downward until it passes over them, 85 whence said fingers spring back to normal position, in which they prevent the match from returning to the chamber. On further advance of the match its ends contact with the roughened surfaces 17, whereby its sul- 90 furous end is ignited. It then continues 95 until it just clears the band 12. At this point another groove 11 is so arranged that it becomes engaged by the loop 17; this engagement is abrupt and causes said loop to 100 strike the drum a blow which tosses the match from its groove into the tray 19. Thus it is impossible for the match to stick 105 in its groove and dangerously heat up the chamber containing the remaining matches.

If desirable, an entire box of matches may be inserted in the chamber, after the lower end of the box has been removed, instead of placing the matches directly in the chamber.

Having thus described my invention, 110

what I claim and desire to secure by Letters Patent, is as follows:

1. A match container comprising a chamber inclosed by a casing, a drum having peripheral slots therein mounted rotatably in the bottom thereof, a tray attached to said casing below and forward of said drum, spring fingers adjacent the ends of said drum, and means to tap said drum to throw 10 the match into said tray when said match is clear of said band.

2. A match container comprising a chamber inclosed by a casing, a drum having peripheral slots therein mounted rotatably in 15 the bottom thereof, a tray attached to said casing below and forward of said drum, spring fingers adjacent the ends of said drum to prevent the return of a match into said chamber, and means at the back of said 20 casing to tap the drum so as to throw the match into said tray when said match is clear of said band.

3. A match container comprising a chamber inclosed by a casing, a drum having peripheral slots therein mounted rotatably in 25 the bottom thereof, a tray attached to said casing below and forward of said drum, a curved spring band extending from the forward member of said casing, spring fingers

adjacent the ends of said drum to prevent 30 the return of a match into said chamber, and means to tap said drum to throw the match into said tray when said match has cleared said band, said means comprising a spring member provided with a looped end 35 in peripheral contact with said drum and adapted to fall into one of said slots when coincident with the latter in its peripheral movement.

4. A match container comprising a chamber inclosed by a casing, a drum having peripheral slots therein mounted rotatably in the bottom thereof, a tray attached to said casing, a curved spring band extending from the forward member of said casing, spring 45 fingers adjacent the ends of said drum to prevent the return of a match to said chamber, and means to tap said drum to throw the match into said tray when said match has cleared said band, said means comprising 50 a loop in the lower end of the rear member of said casing adapted to fall into one of said slots when coincident with the latter in its peripheral movement.

Signed at New York, in the county of 55 New York and State of New York, this 22d day of May, A. D. 1919.

HANS HUMM.
